UNITED STATES PATENT OFFICE.

ROBERT PERRY FADDIS, OF SOCORRO, TERRITORY OF NEW MEXICO.

RAILROAD.

SPECIFICATION forming part of Letters Patent No. 391,131, dated October 16, 1888.

Application filed May 19, 1888. Serial No. 274,614. (No model.)

To all whom it may concern:

Be it known that I, ROBERT PERRY FADDIS, of Socorro, in the county of Socorro and Territory of New Mexico, have invented new and 5 useful Improvements in Railroads, of which the following is a specification.

My invention is an improvement in railways, and has for its object to provide a construction which may be easily set up or erected, will be 10 firm and durable in use, which will require but little repairing, and will take not more than from one-third to one-half the timber now used in construction, and in lengths much more easily procured.

15 The invention consists in certain novel constructions and combinations of parts, as will be hereinafter described and claimed.

In the drawings, Figure 1 is a top plan view of a section of a railway constructed according 20 to my invention. Fig. 2 is a cross-section on line $x\ x$, Fig. 1. Fig. 3 is a cross-section on line $y\ y$, Fig. 1; and Fig. 4 is a detail view of one of the metal frames or cribs.

My railway is shown as comprising a succession 25 of metallic frames or cribs fitted to receive the rail-seats, connections between the frames or cribs arranged opposite each other, and also connections between the rails held in said opposite frames or cribs.

30 The frames or cribs A are all alike and may be of such length as may be found most convenient in constructing a road, and from fifteen to twenty-four inches wide, and it is intended in practice to arrange them with about 35 one foot space between the ends of the adjacent frames. The frames are preferably constructed of end pieces or plates, A' A', side rods, A² A², extended between the opposite end plates of the frames at their opposite sides 40 near their upper ends, the base rods A³ A³, extended between plates A' A' near their lower ends, braces a', extended between the adjacent side and base rods, braces a², extended between the rods A² A², braces a³, extended 45 between the rods A³ A³, and fastenings.

The opposite frames A A are connected by cross-braces C, connected at their opposite ends to the inner base-rod A³. It is preferred to form the braces a', a², a³, and C with eyes or 50 openings and to string them on the rods, as shown, this forming a simple inexpensive connection.

The rails D' are spiked or otherwise suitably secured on short blocks or ties D, forming rail-seats. It may be preferred to provide chair-plates E, having upwardly-bent flanges e at their outer ends engaging upon the outer edges of the base of the rails, the said plates being spiked to the seat-blocks, as shown. These seat-blocks D fit down on the base-rods and 55 snugly between the side rods, and may be secured in the cribs or frames by bolts G and cross plates g, as shown, or in other suitable manner. In securing the ends of rods A² A³ in the end plates, A', the said rods may have 60 bolt-heads at one end and nuts at the other; but they are preferably secured by slots 1 in the rods near their ends and wedges or keys 2 driven in said slots, as shown. Connection 65 bars or braces F extend between and connect 70 the rail D', being preferably provided at their outer ends with upturned portions or flanges f, and being spiked at f' on the inner sides of the rails.

The frames or cribs and connections, when 75 put together, form a complete net-work of iron the full width of the track, and the peculiar construction of braces and ties is susceptible of the greatest strength, yet they are simple and can be put together with the greatest ease. 80

The metal may be iron, and wrought or cast, as found most desirable.

The iron crib or frame is put together on the level road-bed and ballasted up by either earth, 85 stone, or other suitable ballast.

It will be understood that the blocks or timbers may be placed in the frames lengthwise, if desired.

In the use of my invention when it is desired to remove one of the blocks or rail seats it is 90 only necessary to remove one of the detachable side rods, A², remove the block, place another in its stead, and replace and secure the side-rod, avoiding the time and trouble of taking up a rail, and leaving the track always ready 95 for a passing train.

Having thus described my invention, what I claim, and desire to secure by Letters Patent, is—

1. An improved railway comprising a crib 100 or frame having a removable or detachable rod or section, a rail seat or seats fitted in said crib or frame, and the rail on said seat, all substantially as described, whereby, when the

- said rod or section is removed, the rail-seat may be removed from the crib without necessitating the displacement of the rail, as and for the purposes specified.
5. 2. The cribs or frames having a number of longitudinally-extended rods or bars and connections between the same, the rail-seats fitted in said cribs or frames, the rails, and fastenings, all combined substantially as set forth.
- 10 3. In a railway, a crib or frame comprising end plates and rods extended between said end plates, the rail seat or seats, and rail, all combined substantially as set forth.
4. In a railway, the crib or frame consisting of the end plates or portions, the side and base rods extended therebetween, and the braces, the rail seat or seats, and the rail, all combined substantially as set forth.
- 15
5. A railway consisting of a succession of metallic frames or cribs, connections between 20 the opposite cribs or frames, the rail-seats fitted in the frames or cribs, the rails secured on the seats, and connections between the rails, substantially as set forth.
6. In a railway, a crib or frame consisting 25 of end plates and a detachable side rod or rods extended between said plates, the rail-seat, and rail, all combined substantially as and for the purposes specified.

ROBERT PERRY FADDIS.
